UNITED STATES PATENT OFFICE.

LOUIS G. WILLIAMS, OF HOPKINSVILLE, KENTUCKY.

MACHINE FOR MINING COAL.

1,043,183.

Specification of Letters Patent.

Patented Nov. 5, 1912.

Application filed October 28, 1911. Serial No. 657,202.

To all whom it may concern:

Be it known that I, LOUIS G. WILLIAMS, a citizen of the United States, residing at Hopkinsville, in the county of Christian and State of Kentucky, have invented new and useful Improvements in Machines for Mining Coal, of which the following is a specification.

This invention relates to an improved machine for mining coal.

Heretofore in the mining of coal explosives have been universally or largely used for the purpose of loosening the coal from the vein, drills being usually employed in order to prepare the holes for the reception of the explosives. Very many lives are each year sacrificed under the prevailing system, sometimes by unforeseen accidents and sometimes owing to carelessness in the handling of explosives.

The present invention has for its principal object to provide a method or system whereby the mining of coal may be effectively carried out either without resorting to the use of explosives or by using the same only in limited quantities as compared with the methods now in vogue.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—Figure 1 is a top plan view of a machine constructed in accordance with the invention. Fig. 2 is a vertical sectional view of the machine taken on the line 2—2 in Fig. 1. Fig. 3 is a vertical sectional view taken on the line 3—3 in Fig. 1. Fig. 4 is a vertical sectional view taken on the line 4—4 in Fig. 1. Fig. 5 is a side elevation of the frame structure of the machine. Fig. 6 is a front elevation of the machine. Fig. 7 is a vertical sectional view

taken on the line 7—7 in Fig. 1. Fig. 8 is a vertical sectional view taken on the line 8—8 in Fig. 1.

Corresponding parts in the several figures are denoted by like characters of reference.

The frame A of the improved machine may consist of a light and durable casting of malleable iron or other suitable material, said frame being suitably reinforced in any customary and convenient manner to provide the necessary strength to resist strain and wear. The frame structure comprises two principal portions which for convenience will be referred to as the inner and outer portions, the inner portion 1 being that which in operation travels in the kerf or cut formed in the coal, while the outer frame portion 2 is that which occupies a position exterior of the cut and which carries the principal portion of the motive mechanism and which for this reason may be made of a thickness exceeding that of the inner frame portion 1. The outer frame portion 2 is also extended forwardly of the inner frame portion, as will be very clearly seen in Fig. 1 of the drawings, for the purpose of supporting the endless cutting apparatus, whereby the horizontal cut or kerf is to be formed. The outer frame portion 2 is equipped with bearings for the main driving shaft 3 which may be actuated by hand by means of a crank applied to a squared portion 4 of said shaft, or power may be applied in any suitable manner from any convenient source of power. The shaft 3 carries a spur wheel 5 meshing with a pinion 6 on a counter shaft 7 which is connected by a driving chain 8 with a shaft 9 having a bevel gear 10 meshing with a bevel gear 11 upon a vertical or upright shaft 12 which is thus driven. The forwardly extending portion of the frame is provided with a bracket member 13 which extends laterally in front of the inner portion of the frame, said bracket member affording a bearing for a shaft 14. An endless chain 15 equipped with cutting teeth or chisels 16 is guided over the shafts 12 and 14 which are provided with guide wheels or pulleys 17 shown in dotted lines in Fig. 1.

The counter shaft 7 is extended beyond the inner end of the frame portion 1, and

said shaft constitutes an arbor carrying a circular saw or cutting apparatus 18. The cutting teeth or chisels 19 associated with said rotary cutter or saw may be constructed substantially like the teeth or cutters 16 5 associated with the endless chain 17, said cutters being preferably made detachable for convenience in sharpening and replacing, and said teeth or chisels may be held in 10 position for operation by means of set screws 20 or other suitable means. It will be observed that the rotary cutter 18 in practice occupies a vertical position in a plane at right angles to that in which the endless 15 cutting apparatus formed by the chain 15 is located. The rotary cutter 18 is also preferably positioned in such a manner that the cut or kerf formed thereby will coincide with the inner end of the cut or kerf 20 formed by the endless cutting apparatus.

The inner frame portion 1 supports two longitudinally disposed shafts 21, said shafts being disposed in parallel relation. Each of 25 said shafts carries a worm 22, the threads of which project through apertures in the skeleton frame structure above and below the upper and lower faces of the frame so as to be capable of engaging the upper and lower walls or faces of the horizontal cut or kerf 30 formed by the endless cutting apparatus when the machine is in operation. These worms constitute the feeding apparatus of the device, and said worms are to be made sufficiently stout and heavy to grip the coal 35 for the purpose of feeding the machine to its work.

For the purpose of driving the worm carrying shafts, said shafts are provided at their rear ends with bevel pinions 23 with 40 which bevel pinions 24 upon a countershaft 25 may be made to mesh. The pinions 24 are slidably fitted upon the countershaft 25 with which they are connected for rotation by means of keys or splines 26, and said 45 pinions 24 may be moved longitudinally of the shaft 25 to place them into or out of engagement with the bevel pinions 23 by means of shifting levers 27 pivoted on the frame and connected by means of rods 28 with 50 hand levers 29 fulcrumed upon the outer frame portion 2 and whereby they may be conveniently manipulated. The countershaft 25 carries a worm gear 30 meshing with a worm 31 on the transmission shaft 32 55 which is connected by miter gearing 33 with the main shaft 3 whereby it is driven.

It will be seen that by the mechanism herein described motion will be transmitted from the main shaft to the worm carrying 60 shaft 21, and that said worm carrying shaft may be operated simultaneously or independently, the latter being sometimes desirable in case one end of the machine should lag behind the other end in operation.

65 The counter shaft 25 has been shown as

being equipped with a drum 34 on which a rope or cable 35 is coiled. The free end of this rope or cable may in practice be attached to a fixed point in advance of the machine, when, by operation of the latter, 70 the cable will be coiled upon the drum, thus causing the machine to be advanced.

For the purpose of guiding the machine adjacent to the wall of coal that is being operated upon, gage wheels or rollers 36 are 75 provided, said gage wheels being supported for rotation upon the outer frame portion 2 adjacent to the inner edge of the latter by means of brackets or keepers 37.

In using this improved machine the endless cutting apparatus is presented horizontally to the vein of coal at the mouth or outer end of the entry at a suitable distance below the roof so as to make a horizontal cut or kerf while the rotary cutter 18 makes 80 a vertical cut or incision, as will be clearly understood by reference to Figs. 1, 2 and 6 of the drawings. It will be understood that by repeating the operation two or more vertical as well as horizontal cuts or kerfs may 85 be formed. In preparing the machine for operation, the end of the rope or cable 35 will also be made fast to a fixed point, such as a suitable post or stake, at the inner end of the entry. When the main shaft 3 is 90 rotated, motion will be transmitted to the cutting apparatus, as well as to the feeding apparatus of the machine, the latter being fed forward and supported in position by hand or by any suitable supporting means 95 until the worms 22 firmly engage the horizontal cut or kerf, when the machine will be supported in the horizontal kerf that it makes for itself, the feeding being automatically effected by the worms 22 and the auxiliary apparatus including the drum 34 and the cable 35. The machine is first applied to the right hand wall of the entry, and when the inner end of the latter is reached, 100 the machine may be swung around adjacent to the inner end of the entry and into engagement with the left wall, when by continuing the operation, the machine will finally emerge adjacent to the left hand side of the mouth or entry. After withdrawing 105 the machine, or as the latter becomes sufficiently advanced, the coal may be readily broken down in the shape of blocks of convenient size, the breaking down being effected almost entirely by the weight of the coal 110 itself which may be assisted by the use of wedges or other suitable means.

As will be seen from the foregoing description, the coal mined by the improved machine is reduced to lumps of convenient 115 size for loading into the mining cars, and much unnecessary waste is avoided. The coal being produced in lumps of convenient size will also be found commercially more valuable.

The machine is simple in operation and thoroughly efficient for the purposes for which it is provided.

Having thus described the invention, what is claimed as new, is:—

1. In a machine for mining coal, a frame structure comprising inner and outer frame portions, the outer frame portion being of a thickness exceeding that of the inner frame portion, said outer frame portion being extended in advance of the inner frame portion and provided with a bracket that extends laterally in front of the inner frame portion feeding devices carried by the inner frame portion, vertical shafts supported for rotation at the end of said bracket and in the forwardly extended end of the outer frame portion, an endless horizontal cutting apparatus guided over said shafts, a main driven shaft supported for rotation in the outer frame portion, a counter shaft supported for rotation in the frame and extended beyond the inner edge of the inner frame portion, a vertical cutting member on the counter shaft, means for transmitting motion from the counter shaft to the endless horizontal cutting apparatus, and means for transmitting motion from the driving shaft to the counter shaft.
2. In a machine for mining coal, a frame structure comprising inner and outer frame portions, the outer frame portion being of a thickness exceeding that of the inner frame portion, said outer frame portion being extended in advance of the inner frame portion and provided with a bracket that extends laterally in front of the inner frame portion, vertical shafts supported for rotation at the end of said bracket and in the forwardly extended end of the outer frame portion, an endless horizontal cutting apparatus guided over said shafts, a main driven shaft supported for rotation in the outer frame portion, a counter shaft supported for rotation in the frame and extended beyond the inner edge of the inner frame portion, a vertical cutting member carried by the counter shaft, means for transmitting motion from the counter shaft to the endless horizontal cutting apparatus, means for transmitting motion from the driving shaft to the counter shaft, longitudinal shafts supported for rotation in the inner frame portion, worms on said shafts projecting above and below the upper and lower faces of said frame portion, a transverse shaft supported for rotation in rear of the worm carrying shafts, bevel pinions upon the rear ends of the worm carrying shafts, bevel pinions supported slidably upon the transverse shaft in rear of the worm carrying shafts and connected for rotation with said shaft, means for independently adjusting the slideable pinions with reference to the pinions upon the worm carrying shafts, a winding drum upon the transverse shaft having a rope coiled thereon, and means for transmitting motion to the transverse shaft from the main driven shaft of the machine.

shafts and extending above and below the upper and lower faces of said frame portion, and means for transmitting motion from the main driven shaft to the worm carrying shafts.

3. In a machine for mining coal, a frame structure comprising inner and outer frame portions, the outer frame portion being of a thickness exceeding that of the inner frame portion, said outer frame portion being extended in advance of the inner frame portion and provided with a bracket that extends laterally in front of the inner frame portion, vertical shafts supported for rotation at the end of said bracket and in the forwardly extended end of the outer frame portion, an endless horizontal cutting apparatus guided over said shafts, a main driven shaft supported for rotation in the outer frame portion, a counter shaft supported for rotation in the frame and extended beyond the inner edge of the inner frame portion, a vertical cutting member carried by the counter shaft adjacent to the inner edge of the inner frame portion, means for transmitting motion from the counter shaft to the endless horizontal cutting apparatus, means for transmitting motion from the driving shaft to the counter shaft, longitudinal shafts supported for rotation in the inner frame portion, worms on said shafts projecting above and below the upper and lower faces of said frame portion, a transverse shaft supported for rotation in rear of the worm carrying shafts, bevel pinions upon the rear ends of the worm carrying shafts, bevel pinions supported slidably upon the transverse shaft in rear of the worm carrying shafts and connected for rotation with said shaft, means for independently adjusting the slideable pinions with reference to the pinions upon the worm carrying shafts, a winding drum upon the transverse shaft having a rope coiled thereon, and means for transmitting motion to the transverse shaft from the main driven shaft of the machine.

In testimony whereof I affix my signature in presence of witnesses.
